A. SZILVASY

MAIL BOX DISCHARGING ARRANGEMENT

Filed Nov. 7, 1923

UNITED STATES PATENT OFFICE.

ALOJZ SZILVASY, OF NEW YORK, N. Y.

MAIL-BOX-DISCHARGING ARRANGEMENT.

Application filed November 7, 1923. Serial No. 673,232.

To all whom it may concern:

Be it known that I, ALOJZ SZILVASY, a citizen of Hungary, residing at New York, in the county of New York and State of New York, have invented certain new and useful Improvements in Mail-Box-Discharging Arrangements, of which the following is a specification.

This invention relates generally to public mail boxes in which letters or other articles to be delivered by mail are deposited, the invention having for an object the provision of a novel discharge arrangement for the mail, which facilitates the removal of the mail from the box by the collector.

For further comprehension of the invention, and of the objects and advantages thereof, reference will be had to the following description and accompanying drawing, and to the appended claims in which the various novel features of the invention are more particularly set forth.

Fig. 1 of the drawing is a face view showing my improved mail box.

Fig. 2 is a transverse vertical sectional view thereof taken on the line 2—2 of Fig. 1.

Fig. 3 is a horizontal sectional view taken on the line 3—3 of Fig. 2.

Fig. 4 is an enlarged fragmentary transverse sectional view taken on the line 4—4 of Fig. 3, but showing the door in open position.

Fig. 5 is a fragmentary horizontal sectional view taken on the line 5—5 of Fig. 3.

Fig. 6 is a plan view of the frame fitted into the mouth of the mail bag.

Fig. 7 is a fragmentary transverse vertical sectional view showing the mail bag engaged with the sectional door in the bottom of the box to open the said door.

Fig. 8 is a fragmentary vertical sectional view taken on the line 8—8 of Fig. 5.

In the drawing the reference numeral 10 shows a mail box of ordinary shape and which is provided with an opening 10', closed by a hinged shutter 11, for the introduction of the mail into the box. The mail is discharged from the box through a novel sectional door in the bottom of the box, this door being here shown as comprising a number of flat strips which extend from side to side of the box and have their ends engaged with guide elements, such as shown at 14 in Fig. 8, extending along the sides of the box from front to rear thereof. I have here shown four of these strips which overlap

one another, the front strip extending under the one to the rear of it. The front strip is numbered 15 the rear strip is numbered 16 and the two intermediate strips are each numbered 17. These strips are connected together in a chain by means of pins 18 on the strips 15, 17 which engage in slots 19 in the ends of the strips 17, 16.

To hold the rear strip against displacement in a forward direction, and at the same time to permit of its vertical adjustment as the door opens, this strip has a pair of headed pins such as 20 fixed one to each end thereof and engaging in vertical T-guides 21 on the back of the box. Since the rear door sections are moved upwardly when the door opens, I may provide a sloping shelf 22 on the rear wall of the box 10 and which is spaced upward from the bottom of the box just sufficient distance to accommodate these door sections.

To lock the door in closed position I may provide at each end of the box a hooked element 25 which engages in a suitable recess 26 in the front strip 15 and which is formed on a bolt 27 slidable along the front wall of the box, there being a pair of these bolts as will be understood, which may be moved to release the hooked member 25 from the door strip by means of an ordinary type of cam lock, each bolt having a spring 28 engaged therewith to hold it normally in operative position, or these bolts may be arranged to be released by an element carried upon a mail bag, as will be presently set forth.

The mail discharged from the box may be collected in a suitably constructed bag, a portion of which is indicated at 30, and which has fitted to the mouth thereof a rectangular frame 31 of a length equal to that of the box and which is adapted to engage in transverse guide elements 32 in the sides of the box under the discharge door thereof, and to engage the front strip 15 and open the door when the frame is pushed along said guide elements. As here shown the recesses 26 in the front door section 15 are adapted to be engaged by pins 35 on bell crank levers 36 fulcrumed as at 37 in recess 38 in the frame, these levers having attached thereto cords 39 which lead around pulleys 40 and connect to blocks 41 slidable in the frame and having projecting handles 42 by pressing which latter toward one another the levers 36 are operated to depress the pins 35 against the action of ex-

ansion springs such as 43 which bear on the said levers and hold the pins extended. The pins 35 have beveled headed faces 35' which engage under complementary faces 5 on the hooked members 25 to move the latter out of the recesses 26 and thereby unlock the door.

The mail collector, when taking the mail from the box first unlocks the door by releasing the hooked members 25. He then compresses the handles 42, pulling the pins 35 downward, and inserts the frame 31 into the guide elements 32 until shoulders 31' on the frame bear against the front door section 15, in which position the pins 35 are in registry with the apertures 34 in the said section, the pins springing into the apertures when the handles 42 are released. The frame 31 is then pushed inward, moving the door section 15 ahead of itself, the other sections being successively moved until the parts assume the position shown in Fig. 5 with the door open for discharge of the mail. The frame 31 is then pulled outward and causes the door to close, and operative engagement being effected between the frame and the door by the pins 35. After the door has been closed the pins 35 are released and the bag withdrawn, the door being then locked by a suitable key.

To ensure against rain accidentally entering the bag 30 I may provide the latter with a flap 31' which may be extended up the face of the box and hooked at its upper end to eyes such as 46 on the latter.

Having thus described my invention what I claim as new and desire to protect by Letters Patent of the United States is as follows:

1. A mail box having a discharge door

in the bottom thereof, said door comprising a number of sections overlapping at adjacent edges, and slot and pin connections between the respective sections whereby movement is transmitted from one section to another, the front sections engaging under the rear ones, headed pins on the rear edge of the rearmost section, and vertical guide elements on the rear wall of the box with which said headed pins engage. 45

2. In combination, a mail box having a discharge door in the bottom thereof made up of a number of sections overlapping at adjacent edges, a mail bag having a rectangular frame at the mouth thereof, guide elements on the sides of the box under the said door to receive the said frame, and pins carried by said frame and adapted to engage in apertures in the front door section to establish an operative closing connection between 50 the frame and the door. 55

3. In combination, a mail box having a discharge door in the bottom thereof made up of a number of sections overlapping at adjacent edges, a mail bag having a rectangular frame at the mouth thereof, guide elements on the sides of the box under the said door to receive the said frame, and pins carried by said frame and adapted to engage in apertures in the front door section to establish an operative closing connection between 60 the frame and the door, levers on which said pins are mounted, cords connected to said levers, and blocks slideable in the frame and having said cords attached thereto, said 65 blocks having projecting handles. 70

In testimony whereof I have affixed my signature.

ALOJZ SZILVASY.
